DESIGN FOR A VACUUM PUMP

George A. Becker, San Bruno, Calif., assignor to
Eitel-McCullough, Inc., San Bruno, Calif., a
corporation of California

Application May 29, 1943, Serial No. 110,328

Term of patent 14 years

(Cl. 65—1)

To all whom it may concern:

Be it known that I, George A. Becker, a citizen
of the United States of America and a resident of
San Bruno, county of San Mateo, State of Cali-
fornia, have invented a new, original, and orna-
mental Design for a Vacuum Pump, of which the
following is a specification, reference being had
to the accompanying drawing, forming part
thereof.

Referring to the drawing, the figure is a per-
spective view of a vacuum pump, showing my new
design.

I claim:

The ornamental design for a vacuum pump,
substantially as shown.

GEORGE A. BECKER.
